CLAIM

The ornamental design for a bottle, as shown and described.

DESCRIPTION

FIG. 1 is a perspective view of a bottle that has the design.

FIGS. 2 and 3 are side views of the bottle, the other side views being identical thereto.

FIG. 4 is a bottom view of the bottle; and,

FIG. 5 is a top view of the bottle.

The broken line showing of FIG. 5 is for the purpose of illustrating portions of the bottle and forms no part of the claimed design.
